UNITED STATES PATENT OFFICE.

CHARLES A. DAHL, OF BOSTON, MASSACHUSETTS, ASSIGNOR TO THE REECE BUTTONHOLE MACHINE COMPANY, OF BOSTON, MASSACHUSETTS, A CORPORATION OF MAINE.

BUTTON-SEWING MACHINE.

No. 828,844.

Specification of Letters Patent.

Patented Aug. 14, 1906.

Application filed December 12, 1905. Serial No. 291,451.

To all whom it may concern:

Be it known that I, CHARLES A. DAHL, a citizen of the United States, and a resident of Boston, county of Suffolk, State of Massachusetts, have invented an Improvement in 5 Button-Sewing Machines, of which the following description, in connection with the accompanying drawings, is a specification, like characters on the drawings representing like parts.

This invention relates to the class of machine for sewing on buttons substantially as represented in United States Patent No. 336,831, dated February 23, 1886.

15 In accordance with my invention I have combined with the button-stitching mechanism means whereby it is possible to not only insure an elevated position for the hooked needle whenever the machine is stopped, but also to enable the main shaft of the machine to be turned backwardly while the needle is in its elevated position, the backward movement of the shaft lifting the needle from stopped position to its highest point and at 25 the same time moving the needle backwardly. During this rising and backward movement of the needle the delivery end of the raceway is also moved backwardly and diagonally outwardly from the path of the needle, so 30 that the operator may have access to the parts at the lower end of the raceway and insure the proper position for the eye of the button that said button may be stitched to the material. The eye of the button having 35 been placed in proper position at the delivery end of the raceway, the main shaft of the machine will be started forwardly, and immediately the raceway will be moved into its delivery position and the needle moving downwardly in its descent will enter the eye of the button.

Figure 1 in side elevation represents a sufficient portion of a button-stitching machine with my improvements added to enable my 45 invention to be understood. Fig. 2 is a detail of the cam employed for working the needle and feed. Fig. 3 is a detail showing the delivery end of the raceway and the hooked needle, a cast-off coating therewith, 50 the needle entering the eye of a button, and the presser-foot and part of the work-support. Fig. 4 is a detail showing the upper end of the

hopper and button-raceway. Fig. 4^a is a detail showing the lever L. Fig. 5 is a detail detached, showing the parts in the position 55 they will occupy when the needle is in its upper or starting position, the machine being at rest. Fig. 6 is a view of the same parts, the operator having moved the dog to release the clutch and its pawl. Fig. 7 shows detached 60 the hub to be referred to, together with the dog pivoted thereto. Fig. 8 is a detail showing the main shaft in elevation, the belt-wheel and the hand-wheel being in section.

Referring to the drawings, B represents a 65 work-supporting arm suitably sustained by a base part provided with bearings for a shaft R, provided with a series of cams to be described. E represents a neck or arm forming part of the framework; H, a carrier or sliding 70 frame having suitable bearings to sustain the needle-bar F and cast-off bar G. The rear or right-hand end of the carrier has connected thereto a lever a, (see Fig. 2,) pivoted at a' and provided with a lever a², upon which is mounted a roller a³, said roller being acted upon by the surface a⁴ of a cam fast on the shaft R to vary the movement of the lever, and consequently the extent of sliding movement of the carrier H. 75

80 The lever a is provided with an adjusting device a⁵, shown as a screw that may be turned, the screw acting on the end of the lever a² and changing the normal position of the lever a to provide for spacing the buttons, a spring a⁶ acting to keep the roll a³ in contact with its cam. The upper side of the arm E has connected therewith by bolts a⁷ a stand a⁸. The upper end of the stand (see Figs. 1 and 4) receives a rocker a⁹, provided 85 with a stud a¹⁰, that is extended through a hole in the stand and has applied to it a nut a¹¹, a washer a¹² being interposed between the nut and the stand.

The rocker a⁹ receives a stud or bolt b, that 95 constitutes a pivot for the button-raceway b', said raceway having as a part thereof a hopper b² and a portion b³, which receives any usual member, as a brush, that insures the proper traveling of the buttons thrown into 100 the hopper into the raceway to be taken from the lower or delivery end thereof, the heads of the buttons in traversing the raceway sliding over the face b⁴ of the raceway,

The lower end of the raceway is shaped to sustain the button to be stitched to the material, and the eye of the button is permitted to extend outwardly from the path of the needle, as shown in Fig. 3. The lower end of the raceway has a pivoted gate 7, controlled by a spring surrounding a stud 6, which also constitutes a pivot for the gate.

The needle-bar derives its movement 10 through a lever J, pivoted at K and provided at its end with a link T, the lower end of which is slotted to embrace the shaft R, said link having a roller or other stud that enters a cam-groove 21 (shown by dotted lines) in 15 one of the cams fast on the shaft R.

The button-raceway has connected with it an arm c, slotted at c' to receive a clamping-screw c², carried by a depending stand c³, with which is joined at c⁴ a block c⁵, provided 20 with an upright stud c⁶, a forked lever L straddling said pin, said forked lever, common to United States Patent No. 336,881, serving when the rod g, joined to the block c⁵, is moved rearwardly by or through its connection with the lever 9 to impart to the raceway an outward movement that the button at the end of the raceway and in the eye of which the needle stands may be detached from the raceway.

30 The presser-foot h in its operation is made to clamp the stock while the needle is penetrating the same, it having usual means for raising the same to unclamp the stock while the needle therein feeds the same over the work-support.

The hooked needle will be supplied with a thread, as provided for in said patents, by a thread-carrier located in the work-support, and the needle after it has passed through 40 the eye of the button and the material will draw a loop of thread up through the material and the eye of the button, when the needle will again descend outside the eye of the button and through the first loop and enter 45 the stock, and the needle will then be moved laterally to feed the stock, and the next loop drawn up by the needle will be manipulated, as fully illustrated in Patent No. 336,881, which serves to cast the loop over the head of 50 the button, the stitch being such as represented in United States Patent No. 268,370, dated November 28, 1882.

The parts so far described are common to and are fully described in United States Patent to Mathison, No. 268,369, dated November 28, 1882, and Nos. 336,880 and 336,881, dated February 23, 1886, so that particular operation of the parts need not be herein further described, it being understood that the 60 needle-bar and its reciprocating movements actuates the cast-off, as fully provided for in said patents. and that the needle feeds the stock.

The invention to be herein claimed lies 65 more especially in provision for turning back-

wardly the main shaft of the machine after said shaft has been automatically stopped with the needle out of the material, the needle having failed in its previous descent to enter the eye of the button. With the machine stopped, as stated before, a skipped button may be supplied; but to do so it becomes necessary to turn the main shaft backwardly to raise the needle and move the same backwardly and at the same time to 70 move the lower end of the raceway backwardly and outwardly to thereby expose to the ready access of the operator the endmost button in the raceway, that said button may be properly located therein and its eye be 75 made to project properly from the raceway that it may be entered by the needle when the main shaft of the machine is again started forwardly, which may be done either by hand or through the regular starting or power-transmitting devices. Prior to starting the main shaft of the machine after having turned the shaft backwardly and adjusted the button correctly in the lower end of the raceway the operator will raise the presser-foot, engage the stock thereunder, and draw the same forwardly until the hole made by the needle in its last descent where it failed to enter the eye of the button has been brought into the path of the needle. This provision 90 enables the needle when the machine is again started and the main shaft turned forwardly to not only pass through the eye of a button, but enter the same hole in the material.

The shaft R has screwed to it by a screw g 100 a hub g', having a notch h¹⁰. This hub has a hole that receives loosely a circular portion g² of a clutch dog or device g², having a tailpiece g⁷, that at times engages one or the other of a series of pockets 3, (shown in Fig. 5 as six in 105 number,) cut in the inner side of a plate D', bolted to a clutch-pulley D, loose on shaft R and driven continuously during the regular operation of the machine through a belt thereon that is driven in usual manner from a second belt-pulley, (not shown,) adapted to be clutched to a power-driven shaft of any usual transmitter commonly employed to start and stop sewing-machines, it being understood that 110 when said clutch-pulley is unclutched from said shaft its rotation will be stopped in usual manner. The hub g' has a stud 40, provided with a hole in which is secured one end of a spring h³, the free end of which enters a hole in the tailpiece g⁷ of the clutching device or dog, so that said spring acts normally 115 to turn said clutching device in such direction as to cause the free end of the tailpiece to engage one of the pockets of the plate connected with the clutch-pulley. The hub has 120 a forwardly-projecting wing g⁴, that is convexed at 10 to act against the part g³ of the clutch device or dog g².

The belt-pulley is loose on and turns the shaft only when the tailpiece g⁷ of the dog en- 130

ters one of the pockets 3. On a stud h^x of the framework is pivoted a dog-holder h , with which is connected a link h^2 , leading to a treadle or other manually-controlled device, 5 (not shown,) said link being surrounded by a suitable spring 14, that acts normally to put the dog-holder in the position Fig. 5, where said dog-holder acts against the dog g^2 and retains the tailpiece thereof disengaged from the pockets of the loose pulley D. The dog-holder has a depending ear 20, on which is pivoted a pawl h^9 of elbow shape, the short arm of said pawl having a pin over which is hooked one end of a spring h^8 , the opposite 10 end of which engages a pin 41 of the holder h , said spring acting normally to keep the long end of said pawl borne toward the hub g' . When the operator discovers that the needle has failed to enter correctly the eye of a 15 button, she immediately releases the usual foot-treadle and permits the spring 14 to move the dog-holder into the position Fig. 5 to stop the machine, when the free end of said dog-holder meets the dog g^2 and immediately turns the latter, so that its tailpiece g^7 retires from one of the pockets 3, and immediately the pawl h^9 is moved through the action of the spring h^8 to engage the notch h^{10} of the hub g' , which prevents any rebounding of 20 said hub. While the pawl h^9 engages the notch h^{10} of said hub the tendency of the spring h^8 to act and turn the tail end of the pawl upwardly to enter one of the pockets 3 in the loose pulley or belt wheel is overcome, 25 and the hub is held firmly against rotation by the pawl h^9 .

After stopping the machine through the contact of the dog-holder with said dog the operator will stop the rotation of the said 30 pulley by disconnecting or unclutching the same through the usual transmitter, leaving said pulley loose on shaft R and capable of being turned backwardly thereon or in a direction opposite its regular direction of movement, which is designated by the arrows 22.

When the machine has been stopped, as stated, the point of the ascending needle will be arrested in about the position shown in Fig. 3; but the button shown in Fig. 3 will 35 not be there.

Having stopped the pulley D and also the shaft, as stated, the operator will put her foot on the usual treadle controlling the dog-holder and will depress the treadle, turning said holder from the position Fig. 5 into the position Fig. 6, and as said holder is so moved the pawl h^9 will meet the pin 16, that acts as a fulcrum for said pawl and turns the pawl aside, as shown in Fig. 6, sufficiently to remove said pawl from the notch 10.

With the parts in the condition Fig. 6 the operator may engage the hand-wheel R' and turn the main shaft R backwardly for a short distance, which will move the lever J and 40 carrier II in such direction as to raise the

needle-bar in the carrier II and slide said carrier, with the needle-bar and needle, backwardly. At the same time through the link g the lower end of the raceway will be moved backwardly and the lever L (see Figs. 1 and 4a) will cause the lower end of the raceway to be moved outwardly, so positioning the delivery end of the raceway that the operator may have free access to the endmost button in the raceway that the eye of said button 45 may be so presented that it may be entered by the needle when the machine is again started, causing the first of the oncoming pockets of said pulley to act on the tailpiece g^7 of the clutch device to immediately start 50 the shaft R forwardly, which done the carrier II will be moved forwardly and the needle-bar therein will be made to descend, and at this same time the lower or delivery end of the raceway will be moved inwardly 55 and forwardly to place the eye of the button in the path of the descending needle that said button may be sewed to the stock.

When the shaft R is being turned backwardly from the position Fig. 6 by or 60 through the hand-wheel preparatory to getting the endmost button of the raceway in position to be sewed to the stock, the tailpiece g^7 of the dog in engagement with a pocket 3 of the loose pulley D turns said 65 loose pulley backwardly and the tailpiece keeps its engagement with said pocket, so that whenever the pulley D is again started forwardly by power it will act instantly to start the shaft R forwardly. While the 70 parts are in the condition shown in Fig. 6, the operator, through the hand-wheel, may turn the main shaft R both backwardly and forwardly, as may be desired, preparatory to starting the machine by power and making 75 the pulley D effective as the driver for said shaft.

After the main shaft has been started forwardly, the button having been correctly placed, the needle will enter the eye of the 80 button and will secure the same to the material, and as many buttons may be set as may be necessary, one at each rotation of the main shaft, or so long as the operator maintains the dog-holder so that it does not arrest 85 the dog.

Having fully described my invention, what I claim as new, and desire to secure by Letters Patent, is—

1. In a button-sewing machine, button-sewing mechanism, a raceway to deliver buttons, a shaft having a hand-wheel, means moved by said shaft to actuate said mechanism and raceway, a pocketed pulley loose on said shaft, a notched hub fast on said shaft 120 and provided with a dog having a tailpiece, and a dog-holder having a connected pawl to engage the notch of said hub when the dog-holder is in engagement with the said dog, said pawl preventing rebounding of the shaft, 125 130

and means to insure the release of said pawl from the notch in said hub whenever the dog-holder is turned to release said dog.

2. In a button-sewing machine, button-sewing mechanism, a raceway to deliver buttons, a shaft having a hand-wheel, means moved by said shaft to actuate said mechanism and raceway, a pocketed pulley loose on said shaft, a notched hub fast on said shaft and provided with a dog having a tailpiece which projects beyond the exterior periphery of the said loose pulley, and a dog-holder mounted exterior to said pulley and adapted to engage the aforesaid tailpiece of the said dog and a pawl pivotally mounted on said dog-holder and adapted to engage the notch of said hub when the dog-holder is in engagement with said dog, said pawl preventing rebounding of the shaft.
3. In a button-sewing machine, button-sewing mechanism, a raceway to deliver buttons, a shaft having a hand-wheel, means moved by said shaft to actuate said mechanism and raceway, a pocketed pulley loose on said shaft, a notched hub fast on said shaft and provided with a dog having a tailpiece projecting beyond the exterior periphery of said loose pulley, a spring mounted on the aforesaid hub and bearing directly on the locking end of said dog whereby said dog is normally held in engagement with one of the pockets of the said pocketed pulley, a dog-holder pivotally mounted exterior to the

aforesaid loose pulley and adapted to engage the tailpiece of the said dog, said dog-holder being provided with a depending ear in which is mounted a pawl adapted to engage the notch in the aforesaid hub at such time as the dog-holder engages the dog.

4. In a button-sewing machine, button-sewing mechanism, a raceway to deliver buttons, a shaft having a hand-wheel, means moved by said shaft to actuate said mechanism and raceway, a pocketed pulley loose on said shaft, a notched hub fast on said shaft and provided with a dog having a tailpiece which projects beyond the exterior periphery of the said loose pulley, a dog-holder pivotally mounted exterior to said loose pulley and adapted to engage the tailpiece of said dog, said dog-holder being provided with a depending ear, a pawl pivotally mounted in such ear and adapted to engage the notch in the aforesaid hub at such time as the said dog-holder engages the said dog and means for automatically disengaging such pawl simultaneously with the disengagement of the dog and dog-holder.

In testimony whereof I have signed my name to this specification in the presence of two subscribing witnesses.

CHARLES A. DAHL.
